(57) **CLAIM**

The ornamental design for a luggage box lid for a motorcycle, as shown and described.

DESCRIPTION

FIG. 1 is a front and left side perspective view of a luggage box lid for a motorcycle, showing our new design;

FIG. 2 is a rear and right side perspective view thereof;

FIG. 3 is a front elevational view thereof;

FIG. 4 is a top plan view thereof;

FIG. 5 is a bottom plan view thereof; and,

FIG. 6 is a right side elevational view thereof, the left side elevational view being a mirror image thereof.

The broken lines and unshaded surfaces depict unclaimed portions of the luggage box lid.

1 Claim, 6 Drawing Sheets
